(57) **CLAIM**

The ornamental design for a seed reservoir bottle for a wild bird feeder, as shown and described.

DESCRIPTION

FIG. 1 is an isometric view of a seed reservoir bottle for a wild bird feeder showing our new design.

FIG. 2 is a front view of the seed reservoir bottle for a wild bird feeder, the back view being substantially the same.

FIG. 3 is a side view of the seed reservoir bottle for a wild bird feeder.

FIG. 4 is a bottom perspective view of the seed reservoir bottle for a wild bird feeder.

FIG. 5 is a top plan view of the seed reservoir bottle for a wild bird feeder; and,

FIG. 6 is a bottom plan view of the seed reservoir bottle for a wild bird feeder.

The portions of the drawings shown in broken lines form no part of the claimed design.

1 Claim, 5 Drawing Sheets
